OF HOPEDALE, MASSACHUSETTS, A CORPORATION OF MAINE.

WEFT-CLAMPING DEVICE FOR LOOMS.

No. 910,348.

Specification of Letters Patent.

Patented Jan. 19, 1909.

Application filed August 19, 1907. Serial No. 389,128.

To all whom it may concern:

Be it known that I, ALFRED BALDWIN, a citizen of the United States, and a resident of Goffs Falls, in the county of Hillsboro and 5 State of New Hampshire, have invented an Improvement in Weft-Clamping Devices for Looms, of which the following description, in connection with the accompanying drawing, is a specification, like letters on the drawing 10 representing like parts.

This invention in looms has for its object to provide means to prevent slack in the filling laid in the shed until after the warp has been closed on the filling.

15 In fancy looms, as now commonly constructed a shuttle thrown from a shuttle-box at one end of the lay enters the opposite box, contacts with the picker therein, and rebounds before the shed is closed on the filling left therein, the rebound of the shuttle causing slack in that part of the filling in the shed, and as a result thereof the slack filling when beaten in to the fell by the reed presents kinks or loops which show in the fabric 20 and render the same imperfect. So also, due to changes of speed of the loom, as when starting off sometimes at a higher speed than usual, the shuttle is thrown more rapidly as the speed increases and the impact of the 25 shuttle against the picker causes a more sudden rebound which results in formation of slack filling. This uneven rebounding of the shuttle due to its speed as well as to its varying weight caused by the delivery of part of 30 its filling, is noticeable in the fabric being woven, most noticeable when the filling differs in color from the warp, and the fabric produced is designated as "rowey", or in other words the filling makes cross-streaks 35 in the fabric. So also in looms as now commonly made, where a center feeler carried by the lay feels for the filling in the shed, the feeler commonly descends on the filling before the shed is closed thereon, and after the 40 shuttle has entered a box, struck a picker, and has had a chance to rebound.

45 In my studies I have aimed to so construct a loom that the filling will not show kinks or loops, and also to avoid "rowey" streaks 50 in the fabric due to variations in speed of weaving. I ascertain by experiment that these objections common to all looms known to me prior to my invention may be obviated by clamping the filling laid in the shed 55 while yet under the tension of the shuttle

then in its flight into its box, and at the same time closing the shed on the clamped filling.

Consequently my invention consists broadly in mounting on the lay a clamp, and 60 combining therewith means to operate said clamp that it will descend on the filling anywhere between the selvage and the shuttle-boxes, said clamps clamping the filling on the raceway of the lay anywhere between the 65 selvage and the shuttle-boxes, while the shuttle is on its way out of the shed into a shuttle-box, this being done while the lay is being moved forwardly toward the breast beam, the warp not being closed onto the 70 filling laid in the shed until after the clamp has been moved to clamp the filling.

I have made provision to release the filling during the last part of the forward beat of the lay, and to again close the clamp directly on 75 the lay, so that as the lay is moved backwardly away from the breast-beam the clamp cannot possibly catch a filling extended from the selvage to a shuttle in the shuttle-box, and as the lay approaches its 80 back center prior to forming the shed and throwing the shuttle, the clamp is lifted so that the filling will be laid on the raceway, and thereafter the clamp is lowered to clamp the filling as stated. 85

Partially raising the clamp to release the filling thread last laid in the shed and then closing the clamp again on to the lay just prior to the backward movement of the lay 90 enables me to use my invention in connection with drop or shifting shuttle boxes.

My invention is more particularly applicable to fancy looms using drop shuttle-boxes and for weaving woolen cloth, the drop shuttle-boxes being at opposite ends of the 95 lay, and it will be obvious with this class of loom that two clamps are necessitated, one outside each selvage and between the selvage and its adjacent shuttle-box.

In practice the selvage may be acted upon 100 by a usual temple and any usual form of filling-fork carried by the lay may be used.

Figure 1, in front elevation, shows part of the lay of a loom, and drop shuttle boxes of usual construction at each end thereof, together with two filling clamps embodying my invention; Fig. 2 is a top or plan view of the parts shown in Fig. 1 together with the breast beam; Fig. 3 is a section of Fig. 2 in the line 105 x, showing the lay at the extreme back 110

stroke, the shuttle having been thrown through the shed to leave a shot of filling, the clamp being shown as elevated, the shuttle not however having completed its flight; 5 Fig. 4 is a view similar to Fig. 3 but with the lay started forwardly toward the breast-beam, the clamp having been moved to clamp the filling on the raceway of the lay; Fig. 5 is a detail showing the lay substantially in its forward position when the clamp 10 is again lifted automatically to release the filling part of which has been beaten into the fell of the cloth; Fig. 6 is a detail chiefly to show the auxiliary lifter, and Fig. 7 is an enlarged detail of the arm b^3 and its pivotally mounted, bent end 2.

Referring to the drawings, A represents part of a loom frame, A' the breast-beam, A² the lay moved in any usual way, A³ the reed, 20 A⁴ usual drop shuttle-boxes, at the opposite ends of the lay according to the number of shuttles it is desired to use in weaving, said shuttle-boxes being moved in any usual manner and being controlled as to their time of 25 movement by any usual pattern-surface; and A⁵, A⁶ represent usual harness frames having usual heddles to receive and move the warp threads a in the formation of sheds in the warps in any desired order after the manner of any usual closed or open shed looms.

The shed-forming mechanism may be of any usual construction common to looms, and hence need not be herein fully shown, it being understood that the shed is opened 35 during the backward stroke of the lay, that a shuttle B at the level of the raceway of the lay and having the filling to be laid in the shed, may be thrown across the raceway and through the shed, and that as the lay is 40 moved forward toward the breast-beam and prior to the completion of the flight of the shuttle into the shuttle-box to meet the usual picker the clamp will be moved to clamp the filling.

45 To the bottom of the lay I connect a stand b having a stud b' that serves as a pivot for a block b^2 that receives the shank of an arm b^3 having its front end 2 next the breast-beam bent at an angle to said arm, that it may operate as hereinafter described. The end 2 of said arm is pivoted at 3 to the end of the arm b^3 and a spring 4, see Figs. 2 and 7 acts normally to keep a small shoulder of said front end against the inner side of the arm b^3 , said 50 spring yielding should the end 2 catch upon any object during the backward movement of the lay from the breast-beam that otherwise might break the arm or some other part of the loom. The shank of arm b^3 is adjusted 55 by or through a screw b^4 .

The block b^2 receives the end of a link b^8 jointed to an arm b^9 fixed as herein shown to a hollow rock-shaft b^{10} sustained in suitable bearings c , c' connected to the lay, said shaft 60 as shown having two collars c^8 , c^4 , connected

therewith and abutting said bearing to restrain longitudinal movement of the shaft b^{10} in said bearing. The shaft b^{10} is also extended through a bearing c^2 , and is surrounded by a spring c^6 connected at one end with the bearing c and at the other end with the bearing c^2 , said spring acting normally to turn said rock-shaft in the direction of the arrow Fig. 3, the direction in which it is moved when the clamps to be described are 75 lowered or moved toward the raceway of the lay.

The rock-shaft referred to is hollow, and receives in its opposite ends two shafts d , d' , each shaft being adjustable in said rock-shaft and held in its adjusted position by a like set screw 5.

Each of the shafts d , d' , has secured to it in any suitable manner two like blocks 7 to which is secured by like set screws c^6 like filling-clamps c^7 . The outside ends of the shafts d , d' enter respectively like bearings d^2 having feet d^3 that receive each a screw 8 that is extended through a slot in an adjusting plate d^4 secured to the front of the lay by screws d^5 .

By loosening the screws 5 and 8 the shafts d , d' and their bearings may be adjusted toward and from the longitudinal center of the loom to position the clamps correctly to accommodate fabrics of different widths.

Each bearing d^2 has a connected filling rest 10, provided at its end next the breast-beam with a finger or point 12.

In operation the filling extended from the selvage to the different shuttles in the shuttle-box contacts at times with the upper side of the rest and is supported thereby. To the inner side of the breast-beam next the lay I attach by lag screws or bolts e a strand e' , having adjustably connected to it by screws e^1 the upturned end e^2 of a bar e^3 provided at its inner end toward the lay with a shoe e^4 connected adjustably therewith by a set-screw e^5 , the upper side of said shoe receiving

against it and at times sustaining the projecting portion 2 of the bar b^3 as will be described, said arm through the link b^8 turning the rock-shaft b^{10} in such direction as to raise the clamps c^7 , c^{7X} , from the raceway of the lay prior to throwing the shuttle and laying the filling in the shed and on the raceway of the lay. The projection 2 of the arm b^3 is borne normally against the shoe e^4 . The arm e^3 has connected with it at one side a dog e^6 pivoted on a stud e^7 of a plate e^8 attached to said arm by a screw e^9 , said screw extending through a slot of an adjustable stop e^{10} , and a second stop e^{12} also held in adjusted position by a suitable screw 10^X , said stops controlling the extent of movement of the stop e^6 and arresting the stop in its two extreme positions.

To the opposite side of the arm e^3 on a stud f , see Fig. 6, I pivot loosely an auxiliary clamp-lifter f' , having a right-angled lip f^3 , 130

the lower end of which rests normally on the upper edge of the arm e^3 , but said lifter may be turned on the pivot f for a distance limited by the pin 13 extended from said arm into a slot 14. The lifter occupies normally the inclined position shown in the drawings, the projection 2 of the arm b^3 , as the lay is moved forward, passing off the end of said shoe e^4 and being depressed by spring c^5 , and in its movement toward the breast-beam strikes the notched end of the dog e^6 , as shown by full lines Fig. 4, engages the stop, turning the dog on its pivot e^7 thus lifting the portion 2 of an arm b^3 so that its free end acts on the underside of the lip f^3 , said arm passing between the lower end of said lip and the bar c^3 . The raising of the arm b^3 by said dog in moving from the position Fig. 4 into the position Fig. 5 serves to slightly raise the clamps to thereby release the filling, crossing the selvage and leading to the last shuttle thrown, as the lay is completing its forward stroke, the shuttle having fully entered the shuttle-box and the shed having been closed on the filling, this raising of the clamp being effected to release the filling before the completion of the forward stroke of the lay, and while the projection 2 is yet on the dog e^6 . After the projection passes the front end of the lip of the auxiliary clamp-lifter the dog is further turned until it meets the stop e^{10} and is arrested, said projection passing from the shoulder of the dog and striking the upper side of the arm e^3 , said projection descending and striking said arm through the action of the spring c^5 which when released immediately turns the rock-shaft b^{10} to cause the clamps to descend upon the lay prior to the backward movement of the lay. As the lay starts backwardly, the projection 2 meets the lower end of the inclined lip of the auxiliary clamp-lifter, and rides upwardly over said lifter raising the clamp, as shown in Fig. 3, turning the lifter about its pivot f , causing the upper end of the lip to meet the free end of the shoe e^4 , thus making a bridge for the passage of said projection 2 onto the shoe e^4 , said projection passing onto the upper edge of the shoe, which serves to retain the rock-shaft in such position as to maintain the clamps in their elevated positions as the lay completes its back stroke. The lay having completed its back stroke, and the shed having been opened in usual manner, the shuttle is thrown from one of the boxes through the shed to an opposite box, and as the filling is laid in the shed, the lay in its forward movement carries the projection 2 over the top of the shoe e^4 to the end thereof, so that about as the lay has nearly arrived at or about the middle of its forward stroke, said projection under the action of the spring c^5 drops from said shoe and immediately the clamps descend on the filling laid in the shed, said clamps descending on the filling while the same is yet held stretched or under tension and before the shuttle has completed its stroke in the shuttle-box and struck the usual picker. After the clamps descend and meet the filling the shed is closed in usual manner on the filling so that the reed in its further forward movement beats the filling into the fell of the cloth. Now, as stated, when used with drop shuttle boxes the clamps must be lifted to release the filling which is done after the projection 2 of the arm meets the dog e^6 and the clamp must again descend on the lay as the lay completes its forward stroke, and must be held there temporarily while the lay starts back so that the end of the clamps may pass under any filling leading from the selvage to any shuttle, otherwise a filling might possibly get under the clamp. After the lay has been moved backwardly for such a distance as to prevent any possibility of the end of the clamp catching a filling, then the clamp is raised, as described, and maintained in its elevated position while the shuttle is thrown across the open shed, and as the lay again comes forwardly the clamp is depressed instantly at the proper time to clamp the filling while in its stretched position in the shed and prior to closing the shed onto and beating the filling into the fell.

It will be understood that should the bent portion 2 of arm b^3 in the backward movement of the lay be obstructed, said arm may yield.

I have illustrated my invention in connection with drop shuttle-boxes at the end of the lay, but it will be understood that if my filling clamp is used on an ordinary loom, the clamp will be raised only at the back stroke of the lay preparatory to throwing the shuttle through the shed.

I provide the upper side of the race of the lay with a friction device 40 preferably of felt, cloth, leather or india rubber immediately at the point where the clamp descends upon the lay.

Having described my invention what I claim as new and desire to secure by Letters Patent is:—

1. In a loom, a lay, clamps carried thereby, and means located entirely below the plane of the shuttle raceway to actuate the said clamps to clamp the filling crossing the selvage prior to the completion of the flight of the shuttle.

2. In a loom, a filling clamp carried by the lay, means located entirely below the plane of the shuttle raceway to move the same to clamp the stretched filling on the raceway of the lay during part of the forward movement of the lay, and means located entirely below the plane of the shuttle raceway for moving said clamp to release the filling prior to the completion of the forward stroke of the lay.

3. In a loom, a lay, a filling clamp carried thereby, means for moving the same to lower said clamp just before the commencement of the backward movement of the lay so that the clamp may pass under filling threads leading from the selvage, and means for then raising the clamp during the latter part of the backward movement of the lay that the filling may be laid on the raceway.
4. In a loom, a lay, a filling clamp carried thereby, means for raising said clamp during the latter part of the forward beat of the lay to release the filling, and then to lower said clamp just before the commencement of the backward movement of the lay so as to prevent the clamp from catching in the filling, and means for raising the clamp during the latter part of the backward movement of the lay so that the filling may be laid on the raceway.
5. In a loom, a lay, a filling clamp carried thereby, and means for moving the same to raise said clamp during the back stroke of the lay that the filling may be laid on the raceway of the lay, said means causing the clamp to descend on the filling on the lay during the forward stroke of the lay, and means for again raising the clamp prior to the completion of the forward stroke of the lay to release the filling.
6. In a loom, a lay, a rock-shaft, bearings therefor carried by the lay, a shaft at each end of said rock-shaft, means to connect said shafts adjustably with said rock-shaft, a block mounted on each of said adjustable shafts, and a clamp carried by each block, the adjustment of the shafts in the rock-shaft providing for weaving fabrics of different widths.
7. In a fancy loom having a lay and a series of drop shuttle-boxes at each end of the lay, a rock-shaft carried by the lay, two clamps operatively connected with said rock-shaft, and means to turn said rock-shaft to cause said clamps to approach the lay after a filling has been laid in the shed and prior to the completion of the flight of the shuttle.
8. In a loom, a lay therefor carried by a rock-shaft, bearings therefor carried by the lay, a clamp, means for connecting said clamp with said rock-shaft, a stand connected with the under side of the lay, a block pivoted in said stand, an arm sustained by said block, said arm having a jointed spring-sustained projection, means connecting said block with said rock-shaft, a dog adapted to be turned by the projection of said arm, and means for sustaining said dog.

In testimony whereof, I have signed my name to this specification, in the presence of two subscribing witnesses.

ALFRED BALDWIN.
